(57) **CLAIM**

The ornamental design for a bracket with suction cup as shown and described.

DESCRIPTION

FIG. 1 is a top perspective view of a bracket with suction cup showing my new design;

FIG. 2 is a bottom perspective view thereof;

FIG. 3 is a top plan view thereof;

FIG. 4 is a bottom plan view thereof;

FIG. 5 is a right side view thereof;

FIG. 6 is a left side view thereof;

FIG. 7 is a front view thereof;

FIG. 8 is a rear view thereof; and,

FIG. 9 is an enlarged view of portion 9 in FIG. 1.

The dash-dash broken lines in the drawings depict portions of the bracket with suction cup that form no part of the claimed design. The dot-dash-dot broken lines in the drawings depict boundaries of the enlarged areas that form no part of the claimed design.
